UNITED STATES PATENT OFFICE.

JAMES W. HOBBS, OF BOSTON, MASSACHUSETTS.

DESIGN FOR PEPPER OR SALT RECEPTACLES.

Specification forming part of Design No. **11,293**, dated July 8, 1879; application filed June 14, 1879.
[Term of patent 7 years.]

To all whom it may concern:

Be it known that I, JAMES W. HOBBS, of Boston, Massachusetts, have originated a Design for Bottles or Receptacles for Holding Pepper or Salt, of which the following is a full, clear, and exact description, reference being had to the accompanying drawings, making a part of this specification.

Figure 1 represents a side view of my design. Fig. 2 represents a sectional view of the same. Fig. 3 represents a side view of a slightly-modified form, and Fig. 4 represents a rear view of a portion of the design shown in Fig. 3.

My design consists in a bottle or hollow receptacle, A, in the form of a dog, preferably in a sitting position. Said receptacle is preferably of white metal; but it may be of glass or other desired material.

The head *h* of the dog is removable from the body *b*, and is provided in its back portion with suitable perforations *p*, for the escape of salt or pepper when the receptacle is inverted and shaken.

The head is preferably screwed to the body, being provided with an externally-threaded flange, *f*, which engages with an internal thread on the body.

The head and body are enlarged at the point where they join each other to form a collar, *c*, which has the effect to make the joint between the head and body less conspicuous. It is obvious that any breed or variety of dog may be represented, as shown in Figs. 1 and 3, Fig. 1 representing a mastiff, and Fig. 3 an English pug.

When a pair of receptacles is used, they may represent the two varieties shown, or other varieties, and thus give a pleasing effect to a table or sideboard when placed at opposite ends of the same.

In case the receptacle is made of glass, the collar *c* and the threaded portions of the head and body would be preferably metallic.

I claim as my design—

The design for pepper or salt receptacles, substantially as shown.

In testimony whereof I have signed my name to this specification, in the presence of two subscribing witnesses, this 11th day of June, 1879.

JAMES W. HOBBS.
